LEON INGRASSIA, OF ASTORIA, NEW YORK

PAD AND ASSOCIATED TUBE-FORMING MEANS FOR PERMANENT HAIR WAVING

Application filed August 30, 1927. Serial No. 216,366.

This invention relates to devices employed in the permanent waving of hair, and particularly to means for applying the hair-treating chemicals to the hair.

5 In the art of permanently waving hair, as now commonly practiced, a pad containing or saturated with hair-treating chemicals is wrapped, in a wet or moist condition, about the coil of hair to be treated, and the pad 10 and the coil are then usually inserted in a paper or pasteboard tube, over which the heater is then placed after the tube has been suitably crimped and clamped at its end adjacent to the head. This method of preparing 15 the hair for permanent waving involves some inconvenience both in putting the tube in place and in removing it after the heating operation.

The present invention aims to facilitate 20 the preparation of the hair for the heating operation by so combining means for forming the tube with the pad which contains or is saturated with the chemicals that the two may be applied to the hair in one continuous 25 operation and in a very simple manner. The invention further aims so to combine the chemical-containing pad with the tube-forming means that not only can the pad be applied to the coil to be permanently 30 waved and the tube be formed easily and as one continuous operation, but also the tube and the pad may quickly and conveniently be removed from the coil at the end of the heating operation.

35 Other objects and important features of the invention will appear from the following description and claims when considered in connection with the accompanying drawings, in which—

40 Fig. 1 is a plan view of a pad combined with tube-forming means embodying the present invention in substantially flat condition;

Fig. 2 is a transverse section through the 45 combined structure shown in Fig. 1;

Fig. 3 shows the first step of preparing the combined pad and tube-forming means for use;

Fig. 4 is a transverse section of Fig. 3; 50 Fig. 5 shows the combined pad and tube-

forming means wrapped about the coil of hair to be permanently waved;

Fig. 6 shows the tube crimped and clamped and also twisted into the preferred condition for the application of the heater;

Fig. 7 is a section on the line 7—7 of Fig. 6; and

Fig. 8 is a plan view similar to Fig. 1, showing a pad of modified outline.

As shown in Fig. 1 of the drawings, the pad portion 2 of my combined pad and tube-forming means is either of the shape shown in Fig. 1 of the drawings or of the shape shown in Fig. 8, in which that part of the pad 2 which projects beyond the tube-forming means 4 is somewhat narrower than the part which overlaps the tube-forming means 4, the latter part of the pad, in the form shown in Fig. 1, comprising an extension 6 at that end of the pad which, in its wrapped condition about the coil of hair to be permanently waved, is adjacent to the head. In Fig. 8 the projecting portion of the pad is shown as tapered to a shorter edge.

The pad 2, which contains or is saturated with the hair-treating chemicals, may be of any ordinary construction, or it may be made in accordance with or embody one or more of the inventions in my Letters Patent No. 1,531,291, 1,531,292 or 1,581,577.

In the preferred form of the invention shown in Fig. 1, the tube-forming means, which may be a sheet of parchment or other suitable paper of suitable weight for the purpose, is folded once so that one side 7 of the fold overlaps the other side 9 slightly, and the pad 2 is so attached to the folded sheet that the projecting portion of the pad projects beyond the fold thus leaving the two parts of the sheet free to slide upon each other as the sheet is coiled to form the tube. As shown in Fig. 1, the pad 2 is preferably permanently attached to the sheet or tube-forming means 4 as, for example, by gluing it to the sheet, as shown at 8. Furthermore, the tube-forming means 4 is preferably considerably larger in area than the overlapping portion of the pad 2 and the pad is preferably located nearer one end of the sheet 4, or other suitable tube-forming means, than

the other, but preferably not at the end so that there will be some of the tube-forming material beyond the end of the pad. The pad is preferably located nearer that end of the tube-forming means which, in use, will be adjacent to the head, thereby leaving a considerable part of the paper or other suitable tube-forming material extended beyond the other end of the pad, thereby providing material for forming the twist 10 shown in Fig. 6.

In order to secure the tube-forming means 4 in its tubular condition when it has been coiled about the hair to be permanently waved, the margin of one of the folded-over parts of the sheet of parchment paper or other suitable tube-forming material is preferably gummed on that face which will be its inner face in the tube and preferably the margin of the shorter inner part 9 of the folded-over sheet is so gummed, as shown at 12, on that face to which the pad is attached.

The preferred mode of using the combined pad and tube-forming means of the present invention will now be described. One purpose of having a portion of the pad project beyond the tube-forming means is to permit wetting of the pad without wetting the tube-forming means. In the use of the combination, therefore, the operator preferably picks up the pad by taking hold of the paper 4, and then dips that part of the pad which projects beyond the paper 4 into the water and holds it there until it is sufficiently wetted, after which he folds it over on the unwetted portion of the pad, as shown in Fig. 3 of the drawings. He then takes the combined pad and tube-forming means and, placing the right hand margin of it against the coil of hair to be treated, wraps it about the coil into the position shown in Figs. 5 and 7, which will bring the gummed part 12 of the side 9 of the fold over the outer face of the side 7 of the fold, as shown in Fig. 7, to which it may then be caused to adhere. In wrapping it into this position, the operator may take hold of that part of the side 7 of the fold which projects beyond the gummed margin 12 of the side 9, thus keeping his hands out of contact with the adhesive. The tube-forming material may be further secured in its tubular condition by twisting it to form the twist 10 shown in Fig. 6. In fact, twisting is sometimes sufficient to secure the parts in tubular condition without employing the adhesive 12.

It will be seen that because of the fact that the extension 6 of the pad comprises only a single thickness where it is wrapped about the coil to be permanently waved, that this part of the pad and the tubular structure surrounding it can be readily squeezed together by the clamp 14 and thus protect the head 65 during the heating operation. It will be

understood that the coil is wrapped about any suitable curler 16 and that any suitable heater, such as the heater 18, shown in dotted lines in Fig. 6, may be employed.

What is claimed as new is:

1. Combined means for applying hair-treating chemicals to hair for permanent waving and for enclosing the chemical-applying means comprising, in combination, a pad carrying hair-treating chemicals and a sheet of tube-forming material, said pad and said sheet each partially overlapping the other and being secured together, the projection of said pad beyond said sheet being substantially equal to the overlap but the tube length dimension of the overlap being greater than the corresponding dimension of the projection. 70

2. Combined means for applying hair-treating chemicals to hair for permanent waving and for enclosing the chemical-applying means comprising, in combination, a pad having therein hair-treating chemicals and a sheet of tube-forming material, said pad and said sheet each partially overlapping the other and being secured together, said pad extending beyond the tube-forming material so as to permit the portion so extending to be dipped in liquid without wetting the tube-forming material and being of a flexibility to permit folding of the projecting portion thereof after it is dipped in liquid and upon the overlapping portion thereof before coiling about the hair to be treated and the projection of said pad beyond said sheet being substantially equal to the overlap so that when the projecting portion is folded back a pad will be formed of double thickness and substantially the size required for forming the hair treating portion of the tube. 85 90 95

3. A combined pad and means for forming a pad-encircling tube for use in permanent hair-waving comprising, in combination, a pad carrying hair-treating chemicals and a sheet of tube-forming material overlapping a portion of said pad and attached thereto, the overlapping portion of the pad having a tube length dimension greater than the corresponding dimension of the free portion of the pad. 100 110 115

4. A combined pad and means for forming a pad-encircling tube for use in permanent hair waving comprising, in combination, a pad carrying hair-treating chemicals and a sheet of tube-forming material overlapping a portion of said pad and attached thereto, the overlapping portion of the pad being extended beyond the projecting portion of the pad at that end of the pad which in use is adjacent to the head. 120 125

5. Combined means for applying hair-treating chemicals to the hair for permanent waving and for enclosing the chemical-applying means comprising, in combination, a 130

pad carrying hair-treating chemicals and a sheet of tube-forming material so folded upon itself that one of the folded sides projects beyond the other said folded sheet and the folded edge thereof partially overlapping said pad, said pad being secured to the shorter side only of said folded sheet and the free margin of the shorter side of said folded sheet being gummed on that side to which the pad is attached.

6. A combined hair-treating pad and tube-forming structure for use in permanent hair waving comprising, in combination, a sheet of tube-forming material folded upon itself so that one side of the fold projects beyond the other, a pad carrying hair-treating chemicals, overlapping the fold and attached to the shorter of the folded sides of said sheet, the projection of the pad beyond the fold being substantially equal to the overlap of the pad on the sheet so that a portion of said pad may be dipped in liquid without wetting the tube-forming material.

7. A combined pad and tube-forming structure for use in permanent hair-waving comprising, in combination, a pad having therein hair-treating chemicals and a sheet of tube-forming material overlapping a portion of said pad and permanently attached thereto, the projection of said pad beyond said sheet being substantially equal to the overlap so that a portion of said pad may be dipped in liquid without wetting the tube-forming material.

8. A combined pad and tube-forming means for use in permanent hair waving comprising in combination a sheet of tube-forming material, a pad carrying hair treating chemicals overlapping and secured to said tube-forming material and extending beyond the same so that a portion of said pad may be dipped in liquid without wetting the tube-forming material.

9. Combined hair-treating pad and tube-forming structure for use in permanent hair waving comprising a sheet of tube-forming material, a treating pad of absorbent material secured to one side thereof adjacent one edge and extending only part way across the sheet of tube forming material, and a strip of material adapted to become adhesive when moistened which is adjacent to but spaced inwardly a substantial distance from the opposite edge.

10. Combined means for applying hair-treating chemicals to hair for permanent waving and for enclosing the chemical-applying means comprising, in combination, an absorbent pad capable when wet of being folded upon itself and a sheet of relatively non-absorbent tube-forming material, said pad and said sheet each partially overlapping the other and being secured thereto, the portion of the pad which extends beyond the tube-forming sheet being not less than

the portion which is in overlapping relation thereto, so that when the projecting portion is folded back a pad will be formed of double thickness and substantially the size required for forming the hair treating portion of the tube.

Signed at San Francisco, California, this 25th day of July, 1927.
